UNITED STATES PATENT OFFICE.

CLARENCE C. WILSON, OF BRIDGEPORT, CONNECTICUT, ASSIGNOR TO THE WARNER BROTHERS COMPANY, OF BRIDGEPORT, CONNECTICUT, A CORPORATION OF CONNECTICUT.

SHIRT-BOX.

1,115,639.

Specification of Letters Patent.

Patented Nov. 3, 1914.

Application filed April 13, 1912. Serial No. 690,592.

To all whom it may concern:

Be it known that I, CLARENCE C. WILSON, a citizen of the United States of America, residing at Bridgeport, Fairfield county, Connecticut, have invented a new and useful Improvement in Shirt-Boxes, of which the following is a specification.

My invention relates to a new and improved shirt box of the kind adapted to hold each a single shirt, starched and ready for immediate use, and the object of my invention is to provide a means whereby a shirt may be placed in a protective covering at the shirt factory for example, and not removed therefrom, and exposed to handling and consequent contamination, until it reaches the hand of the wearer.

Further objects of my invention are to provide means for observing the kind and character of the material and the size of the shirt without the necessity of removing the same from the box. The purchaser of the shirt is thus assured of absolute cleanliness, while at the same time, he may inform himself of the color, size and material of the garment.

In the following I have described, in connection with the accompanying drawings, one form of shirt box illustrating my invention, the features thereof being more particularly pointed out hereinafter in the claims.

In the drawings Figure 1 is a plan view from beneath of the blank showing the manner of constructing the box; Fig. 2 is a top plan view of the box made up; Fig. 3 is an end view of the cuff end of the box and Fig. 4 is a side elevation of the box.

Similar numerals of reference indicate similar parts throughout the several views.

The blank shown in Fig. 1 comprises a top 5, a bottom 6, a straight edged flap 7, a curved edged flap 8 with securing flanges 9 and securing tabs 10, 10. The scorings are indicated by dotted lines. A V-shaped opening 11 is shown in the top 5 (indicated by dotted lines) and is adapted to be covered by paraffined paper 12, or other suit-

able transparent material. This opening is designed to display the material of the shirt to the purchaser so that he may observe the color and character thereof. A star-shaped opening 13 is shown in the bottom 6 (indicated by dotted lines) and is also adapted to be covered by paraffined paper or other suitable transparent material. This opening is designed to display the marks indicating size, etc., of the garment.

In Fig. 2 I have shown the representation of a coat and collar on the front or top of the box about the V-shaped opening, to assist the purchaser in determining as to the appearance of the shirt when in use. One end of the box is bulged as shown in Figs. 3 and 4 to accommodate the cuffs and prevent them from being crushed. The cuffs are generally starched and ironed so that they do not lie flat and hence extend above the plane of the rest of the garment. I obtain this bulge by providing a flap 8 at one end of the box, with a curved edge adapted to expand that end of the box when in position, the flanges 9 being turned inwardly under the cover and preventing displacement of flap 8.

The blank, formed as described, is made into a box by folding the same at the scorings and securing edge 14 to edge 15 by glue or other suitable securing means. The tabs 10 in connection with flaps 7 and 8 completely close the ends of the box. The ends of the box may be sealed if desired.

As it is obvious that the particular shape of the box, size and shape of the openings forming peep holes thereinto and the location of said openings respectively, whether on the front or back of the box is immaterial and may be widely varied without departing from the spirit of my invention, I do not restrict myself to such details further than the scope of the appended claims demand.

What I claim and desire to secure by Letters Patent is:

1. A shirt box, having a top and a bottom, a rectangular portion at one end, a

bulged portion at the other end and a curved-edge end-flap closing the bulged end.

2. A shirt box, having a top and a bottom, a rectangular portion at one end, a bulged portion at the other end, a curved-edge end-flap closing the bulged end and flanges on the flap adapted to be turned within the box.

In testimony whereof I have signed this specification in the presence of two subscribing witnesses.

CLARENCE C. WILSON.
